METAL FRAME FOR CONSTRUCTING
BUILDING BOARDS

Albert Rafter, Glen Ridge, N. J., assignor to
Rafter Machine Company, Belleville, N. J., a
partnership composed of Albert Rafter and
John C. Rafter, Jr.

Application October 28, 1933, Serial No. 695,625

3 Claims. (Cl. 189—36)

This invention relates to improvements in metallic frames used in the manufacture of building boards made of gypsum, or compositions of matter of a similar nature.

Boards made of gypsum or a composition of matter of a similar nature are at present being extensively used in building construction for flooring, walls, ceilings, roofing, etc. These boards are fireproof and durable and have been found superior in many respects to wood and other types of composition wallboard. The boards made of gypsum or of compositions of matter of a similar nature, are commonly made in sizes of about ten feet in length, fifteen inches wide and about two inches thick.

In the construction of a board, a metallic channelled frame of rectangular shape is employed, to serve as a support for the gypsum and to enable the boards to be mounted in a practical manner for making a floor, wall or the like, and also to enable the boards to be transported without damage.

Heretofore, the rectangular frames have been made of four channelled pieces having mitered ends to enable them to be fitted together at the corners of the frame, after which they are placed in a mold and the gypsum or similar material is poured out into a flat, board-like structure with its edges fitted in the channel of the frame.

It is an object of this invention to provide a rectangular frame which can be formed from two channel members, each of the channelled members being provided with means to enable it to be bent intermediate its length so as to form two sides of a frame.

When gypsum or similar material is poured into a frame made of four channelled sections or of two sections as above described, considerable stresses are thrown upon the frame with the result that the frame is unstable at the corners and tends to spread, causing the board to crack in various places.

Also a great deal of time and labor is necessary in assembling a frame, the frames constantly having a tendency to bend at the corners, resulting in an unsatisfactory break of the board in the majority of cases.

It is an object of this invention to provide supporting plates at the corners of the frame members to prevent bending or shifting movement of any kind from the sides of the frame members, said plates being attached to the sides of the frames by suitable means.

During the process of forming a gypsum board with its frame, it is necessary to prevent spread-

ing or inward bending of the longitudinal sides of the frame during the molding of the board of gypsum or similar material.

Heretofore attempts have been made to overcome this difficulty by providing a curved wire between the longitudinal sides of the frame, but this method has been found objectionable in that the wire tends to straighten outwardly as the gypsum or similar material begins to set, causing the sides of the frame to bend outwardly, which results in the gypsum or similar material of the board being insecurely and improperly held to the frame member.

It is an object of this invention to provide a novel brace between the longitudinal sides of the frame member, which brace prevents outward or inward bending of the longitudinal sides of the frame.

These and other advantageous objects which will later appear, are accomplished by the simple and practical construction and arrangement of parts hereinafter described and exhibited in the accompanying drawings, forming part hereof, and in which:

Fig. 1 is a perspective view of a frame of the class described embodying my invention,

Fig. 2 shows a channel member mitered to enable it to be bent into a right angle to form two sides of the frame,

Fig. 3 is a perspective view showing the manner in which the corners of a frame are held rigid,

Figs. 4 and 5 are perspective views of modified forms of devices for holding the corners of a frame rigid,

Fig. 6 is a perspective view of a preferred form of brace for preventing outward or inward bending of the longitudinal side walls of the frame,

Fig. 7 is a sectional view of a modified form for securing a plate to the frame at the corners thereof to prevent relative movement of the side members of the frame,

Fig. 8 is a sectional view showing the manner in which the brace shown in Fig. 6 is held in a frame,

Fig. 9 is a perspective view of a modified form of frame,

Figs. 10 and 11 are views showing the manner of securing corner strengthening plates to the frame of Fig. 9, and

Figs. 12 and 13 show the manner in which a strengthening brace is secured to the longitudinal sides of the frame of Fig. 9.

Referring to the drawings, in Fig. 1 a metal frame 14 of rectangular shape is shown to be formed from channel members 15 so that the

side walls 16 of the channel members are parallel to the general plane of the frame and the bottom wall 17 of the channel member is at right angles to the side walls 16. In making the frame a 5 channel member 15 is formed as shown in Fig. 2 with an intermediate section thereof mitered at 18 to enable a section on the channel 15 to be bent at right angles to form one half of a complete frame. In order to strengthen the frame 10 and to give rigidity to the corners to prevent relative movement and shifting of the sides so as to maintain a rigid rectangular shape, I position in the channels at the corners of the frame right-angled plates 19 which are secured to the side walls 16 of the channel members by any suitable 15 means, such as spot welding as indicated in Fig. 3.

In Fig. 4, I show another form of securing the plate 19 to the side wall 16. In this form the plate 19 is provided with apertures through which 20 pass tabs 20 punched through the side wall 16, and bent over the plate 19.

In Fig. 5 the plate 19 is provided with slots 25 through which are passed tabs 21, struck out of the side wall 16 and nails or pins 22 are driven through the tabs to prevent withdrawal thereof.

In Fig. 7 the plates 19 are provided with round holes through which is punched metal from the side walls 16 to form grommets 23 for holding the plates 19 to the side walls.

30 In constructing a building block of gypsum or similar compositions of matter, the frames are placed in a mold and the gypsum poured in to fill the channels of the frame and the space between the side walls thereof. During the setting 35 of the gypsum it is necessary that the longitudinal side walls do not bend outwardly or inwardly as such action will obviously cause damaging stresses in the composition of matter, resulting in cracks and insecure holding by the frame. In 40 order to prevent movement of the longitudinal side members, I provide braces 24, as shown in Figs. 1, 6 and 8. Each brace consists of a flat sheet of metal split at each end and bent outwardly to form forks 25 which fit into the channel 45 and rest along the side wall 16 thereof. In order to give rigidity to the brace and prevent bending, ribs 26 are formed therein throughout its length. Braces are inserted in the channels of the longitudinal sides and rest against the bottom walls 50 28 of the channels so that inward movement of the sides is prevented.

As shown in Fig. 8, tabs 27 are punched inwardly from the side walls 16 of the channels and engage the forks 25 to prevent movement of the 55 longitudinal sides of the frame outwardly. It will therefore be seen that when the braces are inserted in the channel in the manner as shown in Fig. 8, a substantial rigid structure is provided, in which there will be no relative movement between the brace and the channel member.

In Fig. 9 is shown a frame member in which the side walls 30 of the channels are provided with inwardly directed flanges 31. With a channel of this structure, strengthening plates 32 are provided at the corners of the frame and positioned in the channel as above explained. With a channel member having the flanges 31, right angled plate 32 is provided with tabs 33 which project through notches in one of the flanges 31 adjacent the corners of the frame, and portions 34 of the flange 31 are bent over the plate 32 to securely hold the latter in position.

With this shape of channel member, a brace 35 is provided so that inward or outward springing or movement of the longitudinal side mem-

bers is positively prevented, the structure of the brace being substantially as described in Fig. 6. However, as shown in Fig. 12 the forks 36 of the brace 35 are inserted in the channel so that the ends of the forks engage the bottom 5 37 of the channel to prevent inward movement of the side walls while the flanges 31 engage the forks to prevent outward movement of the longitudinal sides of the frame.

As far as I know, I am the first to provide a 10 metal channel frame for making building boards from gypsum or a similar composition of matter, wherein said frame is formed from a metal channel strip mitered to enable it to be bent at right angles intermediate its length to form 15 one half of a complete frame.

From the above description it will be seen that I have provided a novel device in the form of the right angled plate 19 and the plate 32 to prevent shifting or relative movement of the sides 20 and to maintain the frame in a rigid rectangular shape at all times.

It will also be seen that the form of brace I have described above is simple in structure 25 and of considerable strength sufficient to prevent either outwardly or inwardly movement of the longitudinal sides of the frame, thus eliminating the possibility of the gypsum or similar composition of matter cracking or being damaged by movement of the sides of the frame as has heretofore been the case with other expedients used in the formation of building boards of the type described.

The several novel elements I have set forth in 35 the construction of my frame have enabled the production of frames of the type herein considered at a considerably less cost than heretofore has been the case and also more conveniently and rapidly, at the same time producing 40 a more satisfactory building board which is not damaged in transportation or during installation by shifting of the sides of the frame.

The foregoing disclosure is to be regarded as 45 descriptive and illustrative only, and not as restrictive or limitative of the invention, of which obviously an embodiment may be constructed including many modifications, without departing from the general scope herein indicated and denoted in the appended claims.

Having thus described my invention, what I 50 claim as new and desire to secure by Letters Patent, is:

1. A frame for the construction of composition building boards, said frame being rectangular in 55 shape and formed from inwardly opening metal channelled members, the side walls of said channels having inwardly directed flanges, right angled metal plates positioned in and lying flat against the side walls of the channels at the 60 corners of the frame, said flanges having recesses therein, and lugs projecting from the plates and tightly fitting in said recesses, said flanges having portions thereof extending downwardly over said plates to secure the plates to the side walls 65 of the frame member.

2. A frame for the construction of composition building boards, said frame being rectangular in 70 shape and formed from inwardly opening metal channelled members, the side walls of said channels having inwardly directed flanges, right angled metal plates positioned in and lying flat against the side walls of the channels at the corners of the frame, said flanges having recesses 75 therein, lugs projecting from the plates and

tightly fitting in said recesses, said flanges having portions thereof extending downwardly over said plates to secure the plates to the side walls of the frame member, and a brace to prevent outward or inward movement of the longitudinal sides of the frame, said brace comprising a flat metal strip having its ends split and bent outwardly to provide forks in different planes which are positioned in the channels and engage the bottom walls thereof.

3. A frame for the construction of composition building boards, said frame being rectangular in shape and formed from inwardly opening metal channelled members, the side walls of said channels having inwardly directed flanges, right angled metal plates positioned in and lying

flat against the side walls of the channels at the corners of the frame, said flanges having recesses therein, lugs projecting from the plates and tightly fitting in said recesses, said flanges having portions thereof extending downwardly over said plates to secure the plates to the side walls of the frame member, a brace to prevent outward or inward movement of the longitudinal sides of the frame, said brace comprising a flat metal strip having its ends split and bent outwardly to provide forks in different planes which are positioned in the channels and engage the bottom walls thereof, and means to prevent withdrawal of the forked portions of the brace from the channel.

15 ALBERT Rafter.
